Primary Examiner — Calvin E Vansant*Assistant Examiner* — Eidiol Ghigliotti Torres(74) *Attorney, Agent, or Firm* — Jeenam Park(57) **CLAIM**

The ornamental design for a car refrigerator, as shown and described.

DESCRIPTION

FIG. 1 is a front elevation view of a car refrigerator showing my design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The dashed or broken lines shown in the drawings depict portions of the car refrigerator in which the design is embodied that form no part of the claimed design.
